LOOM SHUTTLE

Fredric E. Douglas, Hopedale, Mass., assignor to
 Draper Corporation, Hopedale, Mass., a corpora-
 ration of Maine

Application August 12, 1937, Serial No. 157,776

5 Claims. (Cl. 139—207)

The present invention pertains to loom shuttles for bobbin changing looms and more particularly to the bobbin holding means in such shuttles.

Loom shuttles of the type to which my invention applies commonly comprise a shuttle body having a bobbin-receiving cavity and opposed bobbin gripping jaws at one end of the cavity for releasably holding a bobbin in the shuttle. As previously constructed, these jaws were integral-
 ly joined at their shank ends and acted as springs which flexed to grip the bobbin and to permit the bobbin to be inserted into and ejected from the shuttle. In some instances, proper gripping action of such spring jaws is obtainable only by
 making the jaws of such thickness that the required flexing subjects them to very high stresses, which tends to induce breakage of the jaws.

It has been proposed to overcome the aforesaid stresses in the bobbin gripping jaws by providing separate pivoted jaws yieldingly urged together by a coiled compression spring. Such proposed construction has not proven to be successful and is not used commercially, partly because there is not sufficient room in the shuttle body for a coiled compression spring of the required size and strength.

I propose to provide a loom shuttle comprising a shuttle body having a bobbin-receiving cavity as aforesaid, separate opposed bobbin gripping jaws pivotally mounted at one end of the cavity, and a separate spring for yieldingly urging the jaws together, which spring shall be constructed and arranged to provide adequate gripping action of the jaws without being subjected to dangerously high stresses when the jaws are moved by the insertion or ejection of a bobbin.

The aforementioned and other objects of the invention are accomplished in the construction illustrated on the accompanying drawing, of which:

Fig. 1 is a plan view of one end of a shuttle having the preferred embodiment of the invention applied thereto;

Fig. 2 is a view of the same in cross-section; and

Figs. 3, 4 and 5 are detail views, in perspective, of certain parts of the bobbin holding means.

The shuttle shown on the drawing includes the usual wooden body 1 having a longitudinal cavity 2 for receiving the filling carrying bobbin 3. The bobbin is provided with a butt portion 4 which has rings 5, 5 to be gripped by opposed jaws 6 and 7 for holding the bobbin in the cavity 2. In the operation of the shuttle in a loom, the bobbin 3 is ejected from the shuttle and a fresh bobbin 3 is inserted whenever the filling supply F on the bob-

bin becomes substantially exhausted. This changing of bobbins requires that the jaws 6 and 7 separate or move away from each other and then move together to grip the butt of the fresh bobbin.

In the embodiment shown, the bobbin gripping jaws 6 and 7 are separate from each other and are pivoted at their shank ends 8 and 9, respectively. To this end, the shuttle body may be provided with a recess 10 which is located at the end of and communicates with the cavity 2. An inclined bobbin guide 11 is provided with a horizontal top plate 12 and a horizontal bottom plate 13 which are located in the recess 10. The plates 12 and 13 are fixed in the recess as by screws 14 and 15. Two vertical pivot pins 16 and 17 extend between the plates 12 and 13 and have their upper and lower ends fixed in said plates. The shank ends 8 and 9 are positioned in the recess 10 between the plates 12 and 13 and are apertured (see Fig. 4) to receive the pins 16 and 17, whereby the jaws 6 and 7 are separately pivoted in the recess 10.

The jaws 6 and 7 project from the recess 10 into the cavity 2 and, being pivoted, may swing toward and away from each other to permit insertion or ejection of the bobbin. The jaws accordingly need not be capable of flexing intermediate their ends and are preferably of such thickness that they are substantially rigid. Movement of the jaws toward each other may be limited by abutting stop shoulders 18 and 19 formed integrally with the jaws. The exact construction by which the jaws are pivotally supported is not of particular importance except that, as will become apparent, the pivotal axis of the jaws should be at the end of the jaws.

The present invention provides a separate spring for yieldingly urging the jaws 6 and 7 together, the preferred embodiment of such spring being shown at 20 on the drawing. This spring 20 is formed from a flat strip of spring material, preferably steel, bent to extend around the pivoted ends of the bobbin gripping jaws. As thus bent, the spring 20 constitutes an open sided loop of which a portion 21 extends transversely of the pivoted ends 8 and 9 of the jaws. The ends 22 and 23 of the loop are bent or curved around the ends of the jaws and thence toward each other. The ends 22 and 23 of the loop engage the sides 50 of the jaws 6 and 7 being preferably seated in notches 24 and 25 in the jaws.

The particular spring 20 shown extends loosely around the ends of the jaws, i. e., the loop is sufficiently large that the spring does not grip the 55

jaws. The shape of the spring is such, however, that the ends 22 and 23 thereof press against the jaws 6 and 7 and urge the latter together. The points of engagement of the spring ends with the 5 jaws are between the pivot pins 16, 17 and the bobbin engaging ends of the jaws and preferably close to the said pivot pins. A comparatively slight flexing of the spring 20 will permit the bobbin gripping ends of the jaws to separate the 10 required distance. Such slight flexing of the spring precludes any possibility of the spring being subjected to dangerously high stresses.

The advantages of the preferred embodiment, above described, will be obvious and need not be 15 enumerated. Having fully disclosed said preferred embodiment of the invention

I claim:

1. A loom shuttle comprising a shuttle body 20 having a bobbin-receiving cavity and a recess at one end of said cavity, opposed bobbin gripping jaws each pivoted at one end in said recess and projecting into said cavity, and a separate spring comprising an open sided loop of spring material extending around the pivoted ends of said 25 jaws, the ends of said spring loop engaging said jaws and yieldingly urging the same together.

2. A loom shuttle comprising a shuttle body having a bobbin-receiving cavity and a recess at 30 one end of said cavity, opposed bobbin gripping jaws each pivoted at one end in said recess and projecting into said cavity, and a separate spring comprising an open sided loop of flat spring material extending loosely around the pivoted ends of said jaws, the ends of said spring loop being 35 bent toward each other and engaging the sides of said jaws for yieldingly urging the jaws together.

3. A loom shuttle comprising a shuttle body having a bobbin-receiving cavity and a recess at

one end of said cavity, opposed bobbin gripping jaws each pivoted at one end in said recess and projecting into said cavity, said jaws being rigid and being provided with abutting stop shoulders limiting movement of the jaws toward each other, 5 and a separate spring comprising an open sided loop of flat spring material extending around the pivoted ends of said jaws, the ends of said spring loop being bent toward each other and being seated in notches in the sides of said jaws, for 10 yieldingly urging the jaws together.

4. A loom shuttle comprising a shuttle body having a bobbin-receiving cavity and a recess at 15 one end of said cavity, opposed bobbin gripping jaws each separately pivoted at one end in said recess and projecting into said cavity, said jaws being rigid, and a separate spring for yieldingly urging said jaws together, said spring consisting of a strip of flat spring material extending transversely of the pivoted ends of said jaws and having 20 its ends curved around said ends of said jaws and seated in notches in the sides of the latter.

5. A loom shuttle comprising a shuttle body having a bobbin-receiving cavity and a recess at 25 one end of said cavity, top and bottom plates fixed in said recess, two vertical pivot pins fixed to said plates, opposed bobbin gripping jaws having shank portions positioned between said plates and pivoted on said pins, said jaws being rigid and projecting into said cavity, and a separate spring comprising an open sided loop of flat spring material positioned between said plates and extending loosely around the pivoted ends of said jaws, the ends of said spring loop engaging 30 the sides of the shank portions of said jaws and yieldingly urging the jaws together.

FREDRIC E. DOUGLAS.
